Leon Cammen
By his Attorney *F. W. Falter*

UNITED STATES PATENT OFFICE.

LEON CAMMEN, OF NEW YORK, N. Y.

AEROPLANE.

1,294,234.

Specification of Letters Patent. Patented Feb. 11, 1919.

Application filed January 12, 1917. Serial No. 141,938.

To all whom it may concern:

Be it known that I, LEON CAMMEN, a citizen of the United States, and resident of the borough of Manhattan, in the city, county, and State of New York, have invented certain new and useful Improvements in Aeroplanes, of which the following is a specification.

This application, which is a companion case to my application Serial No. 135,551, is directed to means for silencing the exhaust of aeroplane engines.

Taking advantage of the fact that an aeroplane engine is located usually in the forward part of the fuselage and that a muffler compartment may be provided in a rear portion of the fuselage, it is evident that a straight path of travel for the exhaust gases is available, of such extent as to allow these gases to become considerably cooled and reduced in pressure before reaching the muffler device.

Thus I may employ a connecting pipe whose sectional area exceeds that of the exhaust manifold. This pipe may be wholly or in part exposed along the side of the fuselage, to afford a large cooling surface, and may increase in its sectional area toward the muffler compartment.

By these means, *i. e.* length of passage, and increasing sectional area of the exhaust pipe, the velocity of the gases may be so reduced as to set up only a negligible amount of back pressure with any form of muffler device employed.

The muffler itself may be of any desired character to retard the flow of the exhaust gases before passing to the atmosphere.

In the drawing:—

Figure 1 is a plan view of an aeroplane, the supporting wings being broken away.

Fig. 2 is a side elevation of a portion of the fuselage, and

Fig. 3 is a detail view, enlarged, of a portion of the exhaust pipe, showing its connection with the muffler.

In said views the numeral 1 indicates the body portion or fuselage of the aeroplane, having the supporting wings 2. Numeral 3 indicates the engine, located in the forward portion of the fuselage, and 4 indicates a muffler located in the rear inclosed portion of the fuselage, being thus separated by a considerable distance from the engine.

The engine manifold 5 communicates with an exhaust pipe or duct 6, whose transverse

or sectional area exceeds that of the manifold so as to allow the exhaust gases entering said pipe to immediately expand, whereby the velocity of the exhaust gases is reduced, said pipe 6 communicating at its opposite end with an enlarged chamber 7 which may be an inclosed rearward portion of the fuselage, and serving as a muffler approach. Said chamber also contains the muffler 4 which may be of conventional or other character, whereby the entering exhaust gases are given a devious path under well known practice for the purpose of completing the silencing action, by further reducing the speed of travel of the exhaust gases prior to their issuance to the atmosphere.

The exhaust pipe 6 may be of flattened shape vertically and arranged as shown at one side of the fuselage exposed to the action of the atmosphere for cooling purposes, to thus present a relatively large radiating surface. The particular function of the chamber 7 in its enlarged sectional capacity, is that it may produce a fall in pressure of the exhaust gases, greater than the subsequent rise in pressure induced by the muffler with relation to said gases.

I claim:—

1. The combination, in an aeroplane having a fuselage, of an engine and a muffler distantly separated within said fuselage, and a substantially straight line interconnecting pipe, whose sectional area exceeds that of the exhaust manifold with which it connects, to the extent of permitting a fall in pressure in the traversing gases greater than the subsequent rise in pressure therein induced by the muffler.

2. The combination, in an aeroplane having a fuselage, of an engine and a muffler distantly separated within said fuselage, and a substantially straight line interconnecting pipe arranged to permit radiation therefrom, the sectional area of said pipe exceeding that of the exhaust manifold with which it connects, to the extent of permitting a fall in pressure in the traversing gases greater than the subsequent rise in pressure therein induced by the muffler.

3. The combination, in an aeroplane having a fuselage, of an engine and a muffler distantly separated within said fuselage, and a substantially straight line interconnecting pipe, lying partly exposed along the side of the fuselage for heat radiation, the sectional area of said pipe exceeding that of

the exhaust manifold with which it connects, to the extent of permitting a fall in pressure in the traversing gases greater than the subsequent rise in pressure therein induced by the muffler.

4. The combination, in an aeroplane having a central longitudinal body, said body having a motor in its forward portion and a muffler inclosed within its rear portion, 10 of an exhaust pipe of enlarged, flattened section, extending from said motor to said muffler, and lying against the side of the fuselage, the sectional area of said pipe exceeding that of the exhaust manifold with 15 which it connects, to the extent of permitting a fall in pressure in the traversing gases greater than the subsequent rise in pressure therein induced by the muffler.

5. The combination, with an engine and 20 a muffler distantly separated therefrom, of a communicating passage exposed to radiation between the engine manifold and said muffler, the sectional area of said passage, which exceeds that of the manifold, and its 25 length, characterized as permitting, through heat losses and expansion, a fall in pressure of the exhaust gases, greater than the subsequent rise in pressure induced by the muffler, with relation to said gases.

6. The combination, in an aeroplane having a fuselage, of an engine, a muffler distantly separated from said engine and inclosed within said fuselage, and a substantially straight line interconnecting passage, 30 the sectional area of said passage exceeding that of the exhaust manifold with which it connects, to the extent of permitting a fall in pressure in the traversing gases greater than the subsequent rise in pressure therein induced by the muffler. 35

7. The combination, in an aeroplane having a fuselage, of an engine, a muffler distantly separated from said engine and inclosed within said fuselage, a passage extending from said engine toward said muffler, and a chamber of greater sectional area than said passage, connecting said passage and muffler, said passage and chamber being 40 in substantially straight line communication with said engine. 45

Signed at the borough of Manhattan in the city, county and State of New York this 10th day of January A. D. 1916.

LEON CAMMEN.
